UNITED STATES PATENT OFFICE.

HENRY LANGE, OF QUINCY, ILLINOIS.

HINGE.

No. 911,137.

Specification of Letters Patent.

Patented Feb. 2, 1909.

Application filed March 19, 1904. Serial No. 198,957.

To all whom it may concern:

Be it known that I, HENRY LANGE, a citizen of the United States, residing at Quincy, in the county of Adams and State of Illinois, have invented certain new and useful Improvements in Hinges; and I do hereby declare the following to be a full, clear, and exact description of the same, reference being had to the accompanying drawings, forming 10 a part of this specification, and to the figures and letters of reference marked thereon.

This invention relates to improvements in hinges designed more especially for use in connection with covers for cooking utensils, 15 tops of the fuel receptacle of wood burning air tight stoves, etc., and has for its object to provide the hinge with an extension constituting a handle by means of which the cover may be raised, thus avoiding the necessity of 20 taking hold of the cover itself.

To this end the invention consists in certain novel details of construction and combinations and arrangements of parts all as will be now described and the particular features 25 of novelty pointed out in the appended claim.

In the drawings wherein is illustrated the preferred embodiment of the invention—Figure 1 is a perspective view of the upper portion of the fuel receptacle of a stove with 30 cover provided with the improved hinge. Fig. 2, is a similar view with the cover partially raised. Fig. 3, is a side elevation with cover fully raised. Fig. 4 is a sectional view. Fig. 5, is a rear elevation.

Similar letters of reference in the several figures indicate the same parts.

Referring to the drawings the letter A indicates the upper portion of the fuel receptacle, shown as cylindrical, of an air tight stove 40 having a bead *a* around its edge. The cover B for this receptacle, is provided with a downwardly extending portion *b* which fits within the receptacle B, when the cover is in closed position, and with an outwardly extending flange *b*², which rests on the top of the receptacle A when in closed position, all 45 as shown in Figs. 3 and 4.

The hinge by which the cover B is connected to the receptacle B is formed of a single piece of wire of suitable length and weight.

In constructing the hinge, the wire, at equal distances from each end is bent substantially at right angles forming the portions C C, and is then bent slightly upward

and then downward, forming the curved portions *c* *c*. From these curved portions *c* *c*, the wire is then carried inward at substantially right angles forming the portions *c*' *c*', the central portion of the wire being 60 then formed into a loop *c*² extending outwardly at substantially right angles as shown in Figs. 1 and 4.

The portions C C of the hinge are rigidly secured to the cover B, by clips *b*' *b*', and a plate or ear *a*' secured to the receptacle A, is provided or formed with portions *a*² *a*², which are bent over the portions *c*' *c*' of the hinge forming bearings for the hinge as will readily be understood.

When it is desired to raise the cover of the receptacle it is only necessary to grasp the loop or handle portion *c*² of the hinge, or an ordinary stove lid lifter may be inserted in the loop and then by a downward pressure 70 thereon, the cover will be swung upward as will be readily understood. If desired the cover may be raised until the handle or loop portion *c*² of the hinge contacts with the body of the receptacle A, when owing to the 75 angular position of said portion *c*², the cover B, will then be thrown over its pivotal point of connection with the receptacle and will remain in this open position, as shown clearly 80 in Fig. 3.

By forming the hinge with the curved or bent portions *c* *c*, the hinge will take over the bead *a* round the upper edge of the receptacle A and the flange *b* of the cover B.

It will be seen that with a hinge constructed according to this invention, the cover of the stove may be raised without liability of burning or soiling the hands.

While the invention has been shown and described, in connection with a stove, it 95 will of course be understood that it is equally well adapted for use in connection with other articles, such as cooking utensils, etc.

Having thus described my invention, what I claim as new and desired to secure by Letters 100 Patent, is:—

The combination with a receptacle having a beaded edge at the entrance opening and a cover having flanges in angular relation to overlie the beaded edge and project within 105 the receptacle respectively, of a hinge connection between the cover and receptacle embodying a hinge plate secured to the side of the receptacle and having spaced lugs forming bearings in alignment with each 110

other for the pintles, and a pintle and handle member formed of a single length of wire having its ends secured to the top of the cover and parallel to each other, an intermediate portion of each arm being curved to extend out around the flange of the cover and beaded edge of the receptacle, and to extend from the curved portion in alignment with each other to form pintles passing

through from the outer to the inner end of 10 said bearings, the central portion between the bearings being bent to form an outwardly projecting handle; substantially as described.

HENRY LANGE.
